UNITED STATES PATENT OFFICE

FRANCIS X. MALOCSAY, OF SADDLE RIVER, NEW JERSEY

LETTERING DEVICE

Application filed June 26, 1929. Serial No. 373,750.

This invention relates to an improvement in a lettering device or guide, primarily intended for use by draftsmen, artists, engineers and others engaged in making maps, drawings, or the like and has for its object to provide a device which will enable even those unskilled in drawing or lettering to produce letters, figures or numerals having the appearance of those made by printing.

10 A further object of this invention is to provide a guide for making letters and numerals, which guide shall be so arranged and disposed that it will be possible to speedily and with accuracy make fractional numerals 15 as well as other various signs and markings used by draftsmen in designating all sizes and dimensions on drawings. In other words, the device forming the subject matter of this invention provides means whereby 20 letters and numerals of different sizes and arrangements may be very speedily made and the change from a larger letter to a smaller letter or vice versa can be performed without requiring transverse shifting of the 25 lettering guide which usually tends to interrupt the drawing operation while awaiting drying of the ink. This is particularly important where fractional numerals have to be drawn, the same being usually of smaller 30 size than the ordinary numerals indicating dimensions.

With these objects and such other objects as may hereinafter appear, in view, I have devised the particular arrangement of parts 35 hereinafter set forth and more particularly pointed out in the claims appended hereto.

Reference is to be had to the accompanying drawing, in which

40 Figure 1 is a plan view of a lettering guide made in accordance with my invention;

Figure 2 is a similar view of a modified structure;

45 Figure 3 is a plan view of a lettering guide used solely for the purpose of making fractional numerals;

Figure 4 is a sectional view on the line 4—4 of Figure 3, looking in the direction of the arrows;

50 Figure 5 shows the type of fractional nu-

merals capable of being made by any of the lettering guides disclosed in Figures 1 to 3 inclusive;

Figure 6 shows other forms of numerals and signs which can be made by any one of 55 the three lettering guides disclosed in Figures 1 to 3 inclusive; and

Figure 7 discloses various numerals and signs which are made by using either of the lettering guides disclosed in Figures 1 and 2. 60

Throughout the various views of the drawings, similar reference characters designate similar parts.

Referring to the embodiment of my invention disclosed in Figure 1. The lettering 65 guide there shown is preferably composed of a narrow flat strip *a* which may be made of some transparent material such as celluloid or the like. This strip *a* is provided with a continuous elongated groove *b* in its under- 70 surface so that the strip when resting upon the drawing, may be moved over a freshly inked surface, and since the ink letters will lie within the area of the groove *b*, the same are not likely to be blurred or smeared during 75 movement of the strip.

The strip is provided with a series of shaped perforations or openings shown at *c*, *d*, *e*, *f*, *g*, *h* and *i*. The openings just mentioned form a part of a complete group of 80

openings used in producing various numerals. For instance, the two openings *c*¹ and *c*² will produce the numeral 3 if a pen or pencil is first held within the opening *c*¹ and, using a part of the side walls of the same 85 as a guide, is moved to form a part of the letter. Thereupon, the guide is moved a

pre-determined distance to bring the second or complementary opening *c*² to a point adjacent to that where the first opening *c*¹ 90 was located in forming the first part of the letter.

When the second opening *c*² is so positioned, the remainder of the letter or numeral is drawn by placing the pen in this opening *c*² and guiding the same against that 95 part of the wall of the opening as is necessary to produce the remaining part of the letter to complete the same.

It will be seen that in most instances, two 100 openings are required to produce a certain

letter or numeral. For instance, to produce the numeral 5, the two openings indicated at *d* are utilized. For the numeral 6, the two numerals indicated at *e* are used. The numeral 7 requires only the single opening *f*. The numerals 8 and 9 each require two groups of openings indicated at *g* and *h* respectively, while the numeral 0 requires merely the single opening *i*.

10 The portion of the series of openings just mentioned constitutes part of a group required to produce the numerals 1 to 0 inclusive. This group of openings can however, merely produce numerals of a single size. Since in drafting work, the draftsman finds it constantly necessary to indicate fractional dimensions, I provide several series of openings for forming fractional numerals by providing the strip *a* with two similar smaller groups of openings as disclosed at *j* and *k* in Figure 1. These two groups of openings *j* and *k* are so disposed in the structure shown in Figure 1 that one of said groups is located directly above the other.

25 In addition to providing shaped openings for the formation of fractional numerals, I also provide openings shown at *i* and *m* for the formation of plus and minus signs.

30 I also provide a slot *p* for the production of a division line for the fractions and I also provide openings *o* and *p'* for the formation of footage and degree signs.

35 It has been heretofore mentioned that to utilize two openings for making a single numeral or letter, first a portion of one opening is used as a guide in forming a part of the letter and thereupon the strip *a* is slid along on the surface of the drawing paper to bring the second opening in proper alignment to form the balance of the letter. This sliding movement is automatically regulated by means of a slot *r* in which a headed button *s* is freely movable.

45 It will therefore be apparent that to operate the device, the button *s* is held against one end of the slot while one part of the letter is drawn in one of the openings. Thereupon, the finger of the draftsman is placed on the button, holding said button tightly down on the surface of the paper, whereupon the slide is moved so that the button is brought up hard against the opposite end of the slot. This automatically brings the second or complementary opening required for the production of the letter into proper alignment to enable it to be used for the completion of the letter started in the first opening.

55 Since on the guide disclosed in Figure 1, I have provided openings for producing figures of different size, I have accordingly provided two shifting slots. One of said slots is indicated at *r* and the same is used for operating the device to produce the larger let-

ters formed by the larger openings shown at the left hand end of the guide. The other slot *t* and its co-operating button *u* is used for operating the openings comprised in the groups *j* and *k* for forming the fractional numerals. 70

2 In the embodiment of my invention disclosed in Figure 2, the structure heretofore described is utilized except that for the purpose of making a trifle stronger article, the series of openings *j* and *k* are placed one below the other and are staggered with respect to one another. In all other respects, the device is similar to that disclosed in Figure 1. 75

In Figure 3, a small strip is used, the same being used merely for fractions and smaller numerals, the same being similar in all respects to the groups located at the right-hand end of Figure 1, except that it is merely necessary to use the single slot *t* and button *u* rather than two slots and buttons as disclosed in Figures 1 and 2. 80

25 From the foregoing, the benefits and advantages of my improved lettering guide will be readily understood. By arranging the two groups of openings shown at *j* and *k* in the manner indicated, that is, with both of these groups of openings confined within the side limits of the groove *b* and with one group placed higher than the other, it is possible to very readily produce fractional numerals and signs as is disclosed in Figures 5 and 6 without requiring transverse shifting of the guide and the consequent delay incurred in waiting for the inked numerals to dry. 90

35 When groups of openings of the type shown in Figures 1 and 2 are used, it is possible to produce numerals of different sizes including fractions, fractional markings and the like, as for example, disclosed in Figure 7. 105

40 It is of considerable advantage to be enabled to draw fractions, fractional markings and the like and full size numerals from a single guide as the time of the draftsman in making such numerals is greatly conserved. 110

45 While I have described my invention as being applicable to the making of numerals, fractional numerals and the like, it is obvious that the same may be used for making letters of different sizes from the same guide, without departing from the spirit of my invention. 115

55 What I claim is:

1. A device of the character described comprising a strip having a grooved under-face, a pair of similar groups of numeral-forming openings formed in said strip and within the confines of the side edges of the groove, one of said groups being so located above the other that fractional numerals can be formed thereby with longitudinal shifting of the strip only. 125

2. A device of the class described comprising 130

ing an elongated strip having a group of larger character-forming openings and two groups of smaller character-forming openings, one of the groups of smaller character-forming openings being arranged in alignment above the other group of smaller openings, the three groups of openings being adapted for co-operative use in forming large numerals and smaller associated fractional numerals with longitudinal shifting movement of the strip only.

3. A device of the character described comprising a strip having a group of numeral-forming openings in the same for forming large numerals, said strip being provided with two other groups of openings for forming associated fractional numerals, said fraction-forming openings being smaller than those of the first group, a slot in the strip and a button in said slot for guiding in the placement of characters formed by utilizing the group of larger openings, and a similar slot and button for guiding in the placement of characters formed by using the several groups of smaller openings.

Signed at the city, county and State of New York, this 24th day of June, 1929.

FRANCIS X. MALOCSAY.
